METHOD AND APPARATUS FOR PACKAGING
ASPHALT AND CONTAINER THEREFORJames Miller, Jr., Chicago, Ill., assignor to
Trumbull Asphalt Company, a corporation of
Illinois

Application August 2, 1940, Serial No. 349,511

5 Claims. (Cl. 93—39.1)

This invention relates to an improved method and apparatus for packaging asphalt and an improved package or container therefor.

Under the ordinary methods of manufacturing asphalt and using the same, the asphalt is prepared at a manufacturing plant in suitable stills or furnaces and is then placed in containers or packages of various sizes to await purchase by consumers. Asphalt in this condition is almost a solid, although it is capable of some movement having some fluidity. The containers in most instances are of a standard size adapted to hold 100 pounds, 200 pounds or 400 pounds. Smaller and larger containers within reasonable limits can also be provided, if desired.

Various forms of containers have come into general use in the trade. Cylindrical metal drums or containers are one type. Others include paper bags or rectangular fiber or cardboard boxes. The metallic drums must be opened and the contents removed from an open end or the drum must be demolished to remove the asphalt. Paper bags and boxes are, of course, destroyed in removing the asphalt.

Metallic containers are most expensive and naturally increase the cost of asphalt to the consumer. Paper bags and boxes are not satisfactory under certain conditions. The bags tear easily and expose the asphalt to a certain amount of deterioration. The boxes must be firmly built and closed and this involves time consumed and the expense of the materials. Of the types of containers now in use metallic drums or containers are the most preferable but the expense of the same limits their use.

One of the objects of this invention is to provide an improved cylindrical drum or container for asphalt.

A further object of the invention is to provide an improved drum or container constructed of a paper or card-board material which is sufficiently rigid to provide a good package during shipment or storage, but which can be easily destroyed when it is desired to use the asphalt therein.

A further object of the invention is to provide an improved drum or cylindrical container constructed of a paper or card-board material and having means associated therewith for easily splitting or tearing the drum or container so that the asphalt can be removed.

A further object is to provide an improved drum or cylindrical container of the type described constructed of a paper or card-board that has previously been treated upon its in-

terior walls with an "anti-stick" solution so that the asphalt will not adhere to the walls of the container and make the removal of the same difficult.

5 A further object of the invention is to provide a very simple method of constructing the cylindrical container so that the same can easily be made by unskilled workmen at the Asphalt Manufacturing Plant as they are required.

10 A further object is to provide a method of constructing cylindrical containers of the type described wherein the cylinder comprises a body portion and two end or cap portions and the same is assembled by sewing or stitching with metal or other thread.

A further object of the invention is to provide improved apparatus for manufacturing the cylindrical containers mentioned.

Other objects and advantages will be more 20 apparent from the following description wherein reference is had to the accompanying three sheets of drawings upon which—

Figure 1 is a front perspective view of one of the containers constructed in accordance with my invention.

Figure 2 is an enlarged fragmentary sectional view showing the package mutilating cord and is taken on the lines 2—2 of Figure 1.

Figure 3 is an enlarged fragmentary side view 30 showing the manner in which the overlapped sides of the container body are fastened together.

Figure 4 is a front perspective view of a modified construction of cylindrical container showing the manner in which the case is constructed 35 with ordinary stitching of the seams.

Figure 5 is a side elevational view of a stitching machine and container assembling mechanism.

Figure 6 is a fragmentary cross sectional view 40 through the same taken generally on the lines 6—6 of Figure 5.

Figure 7 is a plan view of the container holding mechanism used in constructing the same.

In the embodiment of the invention which I have chosen to illustrate, in Fig. 1 I have shown 45 a cylindrical container 10 which is constructed in accordance with my invention. The container itself comprises the cylindrical shell 12 which is formed of a rectangular sheet of paper that has its edges 14 and 16 folded over and fastened together by a plurality of staples. A bottom cap 18 is provided with a downwardly turned edge 20 which in turn is fastened by a plurality of staples 22 around the lower edge of the body 12 of the container. An upper cap 24 55 may be telescopically mounted within the upper

cylindrical end of the container and be held in position either by friction or by staples if desired. The container thus described is constructed of a comparatively thin cardboard and comprises three elements: a rectangular sheet from which the cylindrical body is formed, and the lower and upper cap or closure members which may be constructed from a similar material.

In order to remove the asphalt from this container and to easily destroy the container during this removal, I have provided a member 26 which may be in the form of a cord or wire and may be fastened against the interior wall of the container and extend the height of the same. The member may also extend around the periphery of the container adjacent the base as shown at 11. The cord 26 may be fastened securely in position adjacent to the upper and lower ends of the container by a pair of staples 28 and 30. As thus constructed, it can be seen that a comparatively simple container has been provided and one which is easily torn open so that the asphalt which is in the form of a cylinder in the same can easily be removed therefrom and used.

In order to prevent the asphalt from adhering to the interior walls of the cylinder, I have provided a coating upon the interior walls of the same so that the hot asphalt which is flowed into the container and hardens does not adhere to the surface. Thus the removal of the container from the asphalt is easily and simply effected. During storage or shipment, the asphalt is protected by the container and is in neat package form so that it can be easily handled and moved about.

In Figure 4 I have shown a similar cylindrical container 10a constructed of similar parts but in which the same are fastened together by either metal or cloth stitching 32 about its edges.

In Figures 5 to 7 I have illustrated generally the method of constructing the containers described and the mechanism for carrying out this operation. Thus in Figure 5 I have shown the usual type of stitching mechanism 40 provided with the base 42, the upright standard 44, and the head 46. The stitching machine 42 may be of the usual type familiar in the art, which includes a wire magazine 46, feed mechanism 48, and clincher mechanism 50 positioned above a block or anvil 52 upon which the work that is to be stapled is placed. Since this type of stitcher is so well known on the market no further explanation of the same will be given.

In assembling the container which I have described the sheet 12 of paper is placed within the cylindrical house or hopper 54 over a plurality of wire guide members 56. The wire guide members may all be fastened at one end in the end wall 58 of the housing 54 and have their opposite ends connected to a collar 60. The collar 60 is slidably mounted upon an axial rod 62. When a sheet of paper is placed in the housing 54 with its edges 14 and 16 overlapping the handle 64 connected by a link 66 to the collar 60 is moved forward with the result that the guide wires 56 spread out and press the sheet 12 against the interior surface of the housing 54, thus forming the container body into a cylindrical shape. An opening defined by the edges 70 is provided in the upper side of the housing 54.

The housing 54 may be carried by a pair of arms 72 connected together by a bracket 74. The bracket 74 may have an axial bore 76 so that it

may be slidably mounted upon a rod 78 parallel with the block or anvil 52. The bracket 74 may further be provided with a pair of radially extended arms 80 and 82 which carry the rollers 84 and 86 respectively. The roller 84 is adapted to ride upon a rail 88 and the roller 86 is adapted to ride below and bearing against a rail 90. The rod 78 and the rails 88 and 90 are supported by suitable bracket members 92 and 94 at their extended ends.

With the construction thus far described it can be seen that when a sheet 12 is placed in the member 54 and fastened in place by guide wires 56, the same may be moved forward below the clincher member 50 of a stitching machine upon the anvil 52 and the staples 22 previously described may be placed in position, thus making the open-ended cylindrical body portion of the container. The end caps may then be placed upon the open-ended cylinder as shown in Figure 2, the cylinder disposed on the anvil 52 with the upper end against the stop member 96 and by rotating the container the staples 22 may be put in position, fastening the end on the container. When it is desired to fasten the upper end on the container after it has been filled with asphalt this may be done with a hand stitching machine or in any other suitable or desirable manner.

From the above and foregoing description it will be apparent to those skilled in the art that I have provided a comparatively simple mechanism for constructing the containers which form the subject matter of this invention. The methods by which the same are constructed are such that they can be carried out by the average unskilled artisan in an asphalt manufacturing plant and the containers can thus be constructed at the factory where the asphalt is being made. While I have not shown the construction of a stitching machine for making the container shown in Figure 4 with continuous stitching instead of with staples it is quite apparent from the construction of the container that the apparatus and method used would be very similar to that herein shown. The stitching machine, while it might of a different type, would be operated in substantially the same manner in combination with the house or form for the cylinders.

From the above and foregoing description it will be apparent to those skilled in the art that I have provided a highly improved container for asphalt which overcomes all of the objections that have been mentioned against the other types of containers known in the art. In addition, I have described a comparatively simple method and apparatus for constructing these containers so that the same can be assembled and made ready for use as asphalt is being prepared.

While I have illustrated and described a specific embodiment of my invention, it will be apparent to those skilled in the art that changes and modifications can be made in the exact details shown and I don't wish to limit myself in any particular, rather what I desire to secure and protect by Letters Patent of the United States is:

1. Apparatus for manufacturing cylindrical containers of paper material comprising a stitching machine having a stitcher head and an anvil disposed therebeneath, a cylindrical shell mounted upon a track for forward movement aligned with said anvil, wire guides within said shell and means associated therewith for forming a

cylindrical container body so that the same may be stapled by said stapling machine.

2. Apparatus for manufacturing cylindrical containers of paper material comprising a stitching machine having a stitcher head and an anvil disposed therebeneath, a cylindrical shell mounted upon a track for forward movement aligned with said anvil, wire guides within said shell and means associated therewith for forming a cylindrical container body out of a rectangular sheet so that the same may be stapled through overlapping edges by said stapling machine.

3. Apparatus for manufacturing cylindrical containers of paper material comprising a stitching machine having a stitcher head and an anvil disposed therebeneath, a cylindrical shell mounted upon a track for forward movement aligned with said anvil, wire guides within said shell and means associated therewith for forming a cylindrical container body out of a cylindrical sheet so that the same may be stapled through overlapping edges by said stapling machine, said guide wires arranged circumferentially within said shell and having a movable collar.

4. Apparatus for manufacturing cylindrical containers of paper material comprising a stitching machine having a stitcher head and an anvil disposed therebeneath, a cylindrical shell mounted upon a track for forward movement aligned

with said anvil, wire guides within said shell and means associated therewith for forming a cylindrical container body out of a cylindrical sheet so that the same may be stapled through overlapping edges by said stapling machine, said guide wires arranged circumferentially within said shell and having a movable collar, and a pivoted lever connected to said collar capable of moving said wire guides outward to form a cylindrical container within said shell.

5. Apparatus for manufacturing cylindrically shaped paper container bodies from a rectangular sheet of paper comprising a stapling machine having a stapling head and an anvil disposed therebeneath, a cylindrical shell member mounted upon parallel guides and aligned with said anvil and so positioned that back and forth movement of said shell will bring the periphery of the same above said anvil, a plurality of circumferentially disposed wire guide members within said shell and adjacent the inner periphery of the same adapted to receive a rectangular sheet of paper and form the same into a cylindrical shape with overlapping edges aligned with said anvil whereby the shell can be moved forward over said anvil and staples can be fastened through said overlapping edges of the paper to form a cylindrical shell.
